UNITED STATES PATENT OFFICE

ARTHUR G. SUTCLIFFE, OF CHICAGO, ILLINOIS, ASSIGNOR TO ILG ELECTRIC VENTILATING COMPANY, OF CHICAGO, ILLINOIS, A CORPORATION OF LOUISIANA

RADIATOR

Application filed June 5, 1930. Serial No. 459,303.

This invention relates to radiators, and, in its chief intended application, to what are known in the art as blast heating radiators, a blast heating radiator being an assembly of heating surfaces employed in connection with a blast of air, or air coming from a fan at high velocity. It is so called to distinguish it from the ordinary radiator used for steam and hot water heating by means of direct radiation or convection. It is well known that the amount of heat obtained from a radiator increases with the air velocity over the radiator, and, therefore, when air passes over a radiator at a high velocity it increases the efficiency of the heating surfaces. Blast heating radiators of this type are quite extensively used for the heating of factories, work shops, and in other similar situations. However, the novel features of the present invention hereinafter described are not limited to their use in a blast heating radiator, but may usefully be employed in radiators of other types.

The present invention is embodied in a radiator comprising a plurality of tubes, and duplicate endwise reversed upper and lower longitudinally tapered headers into which the ends of said tubes are connected. These radiators are frequently mounted quite close to a wall, floor or ceiling of the room; and the invention provides means by which the steam supply and exhaust pipes may be led into the radiator headers from different directions as the circumstances of each installation may require.

The invention, its novel structural features, and the benefits and advantages attending the same will all be readily understood by persons skilled in the art from the following description, taken in connection with the accompanying drawing, in which I have illustrated a simple and practical embodiment of the invention, and wherein—

Fig. 1 is a side elevation of the complete radiator unit.

Fig. 2 is an enlarged vertical longitudinal section, broken out, through the upper portion of the radiator.

Fig. 3 is a vertical transverse section taken on the line 3—3 of Fig. 2.

Fig. 4 is a fragmentary plan view of one of the punched radiator fin strips.

Referring to the drawing, 10 designates the upper hollow header of the radiator and 10' the lower hollow head, these parts being structural duplicates relatively inverted both vertically and horizontally as will be apparent from Fig. 1. 11 and 11' designate the upper and lower header plates, and 12 designates each of one or more rows of tubes, preferably of copper, the upper and lower ends of which are tightly fitted into holes in the upper and lower header plates. 13 designates each of a group of closely associated fins that are mounted on the tubes 12.

Each of the headers 10 and 10' is a hollow casting preferably of the longitudinally tapered form shown in Fig. 1 and formed with a marginal flange 14 that seats on the marginal portion of the header plate, with an interposed gasket 15 to insure a steam tight joint, and is attached to the header plate by screws 16. Each hollow header is provided with a vertical threaded opening 17 at the high end of its top wall, and a similar horizontal threaded opening 18 of the same diameter as opening 17 in the high vertical end wall thereof. This construction provides a double entrance header, whereby steam may be allowed to flow in from either a vertical or a horizontal pipe, and similarly exhaust from the lower header 10'. This allows the heating surface to be put close to a wall, floor or ceiling, depending upon which position is most desirable or convenient. If the unit is mounted close to the ceiling, the top opening 17 is closed by means of a plug 19, and a steam connection is then made by screwing the steam supply pipe 20 into the opening 18 in the end wall. If, on the other hand, it is more desirable or convenient to mount either or both ends of the unit close to a wall, the opening or openings 18 are closed by the plug 19, and the steam pipe is screwed into the vertical opening 17.

As above stated, the radiator tubes 12 are pressed tightly into holes in the header plates 11 and 11'; and into the ends of the tubes are forced internal orifice bushings 21, preferably countersunk or internally flared at

their outer ends as shown at 21', to reduce resistance to the flow of steam, which bushings aid in sealing the joints of the tubes in the header plates against leakage through expansion and contraction, and also increase the frictional grip of the tubes on the plates.

On the tubes 12 are mounted in closely spaced relation a group of radiator fins, each consisting of a sheet metal strip 13, a fragment of which is shown in plan view in Fig. 4. Through this strip are punched holes 22 each of a diameter slightly less than the external diameter of the tubes, and these plates are then driven onto the tubes before the header plates are assembled with the latter. The punching of the holes 22 extrudes metal of the strip where the holes are punched producing more or less irregular depending flanges 13', which serve as spacers between adjacent fins and also give each strip a substantial frictional grip on the tubes. These fins also materially stiffen and strengthen the tube structure.

It will be readily seen from Fig. 1 that the described structure is symmetrical through-

out and can be assembled either end up, with the horizontal pipe leads, when used, entering from either the right or the left, as may be most convenient. The double entrance header feature, especially when combined with endwise reversible upper and lower headers, thus well adapts the structure to situations where the supply and exhaust steam pipes are most conveniently led in from above and below or from either end.

I claim:

A radiator comprising a plurality of tubes, and duplicate endwise reversed upper and lower longitudinally tapered headers into which the ends of said tubes are connected, said upper header being formed with a vertical opening in its top wall and a horizontal opening in its high end wall for optional connection thereto of a flow pipe, and said lower header being formed with a vertical opening in its bottom wall and a horizontal opening in its high end wall for optional connection thereto of a flow pipe.
